UNITED STATES PATENT OFFICE

JOSEPH W. WEISS, OF BALTIMORE, MARYLAND

COLLAPSIBLE CARTON.

1,120,774.

Specification of Letters Patent. Patented Dec. 15, 1914.

Application filed November 9, 1912. Serial No. 730,329.

To all whom it may concern:

Be it known that I, JOSEPH W. WEISS, a citizen of the United States, and a resident of Baltimore, in the State of Maryland, have invented certain new and useful Improvements in Collapsible Cartons, of which the following is a specification.

This invention relates to collapsible cartons, more particularly to the type of carton which is adapted for use as a hat box or some similar box which is adapted for packing an article having considerable bulk.

Boxes or cartons of the above description have been hitherto constructed in three sections, a top, bottom and middle section, the latter being collapsible and when shipped is inserted within the top and bottom sections, the latter telescoping over one another to form a low box in which the middle section may be held. However, this form of collapsible box is not very economical in space in knock-down condition, inasmuch as the top and bottom are permanently set up and occupy considerably more space than is necessary for the amount of actual material used in their construction. Moreover, these boxes as hitherto constructed do not fit very snugly when set up for the reason that the top and bottom sections must be of different sizes in order to telescope within one another, and thus when the entire box is set up, the middle section will not fit snugly in either the top or the bottom as the case may be. To overcome these difficulties, I have devised a carton of this character formed of a stiff, light material such as corrugated board in which all of the three sections are collapsible, so that when the box is shipped, or stored in knock-down condition, it will occupy no more room than the actual amount of material used will warrant, as all of the parts are laid flat one over the other and no idle space is left anywhere.

In carrying out the invention, the top and bottom sections are formed of a single blank which is scored along its lateral and end edges to form side and end portions. The blank is cut in along the side scores preferably in an oblique direction, so as to form the ends with outwardly flaring lateral edges. When the section is set up, these lateral edges of the ends wedge in tightly against the sides and are thus held firmly in place, particularly so by reason of the flexibility of the material adjacent to these lateral edges of the end portions produced by

the scoring. When the top and bottom sections are thus set up, the middle section may be opened up and forced into the bottom section by its engagement with the in-turned flaps. This holds the middle section tightly in place with a snug fit. The top section may then be inserted over the middle section and will also fit snugly, and thus a box is produced which is firm, rigid and not readily deranged. Moreover, when collapsed, the parts occupy very little space, presenting an enormous saving in space as compared with the bulky carton as set up and a considerable saving in space as compared with the collapsible carton of this character such as hitherto used and collapsed in the manner above described.

In the accompanying drawing illustrating one embodiment of this invention Figure 1 is a perspective view illustrating the carton completely set up. Fig. 2 is a perspective view illustrating the bottom section. Fig. 3 is a fragmental, sectional elevation illustrating the wedging effect produced between the middle and bottom sections. Fig. 4 is a perspective view illustrating the sections collapsed lying one on top of another in position for storing or shipping. Fig. 5 is an enlarged fragmental detail view of a corner section of one of the end closures when collapsed to clearly show the oblique edge of the end flap. Fig. 6 is a fragmental enlarged detail view of a corner of the box as set up to show the material of the box as being corrugated.

The carton consists of three sections, top and bottom sections 1 and 2 of substantially similar construction and a middle section 3. The construction of the top and bottom sections is illustrated in Fig. 2. The sections are each formed with a body 4 having sides 5 and ends 6. Tongues 7 extend from the sides and the ends are provided with flaps 8 which fold over the tongues and wedge in against the sides. To produce this wedging action, the lateral edges 9 of the flaps 8 are cut obliquely so as to flare outward as illustrated in Fig. 4. These edges are cut along the scores 10 formed between the body 4 and the sides 5, the material adjacent these edges thus being rendered flexible so as to more tightly wedge in against the sides. The middle section is composed of comparatively high walls bounded by scores 11 along which the material may bend, these walls being united preferably at one edge by a

strip of flexible material 12 such as canvas or the like.

When the box is to be set up, the bottom and top sections are manipulated and set up 5 in the form illustrated in Fig. 2 and then the middle section is opened up and set into the bottom wedging in against the flaps 8 as illustrated in Fig. 3. After the material to be packed is inserted, the top may then 10 be placed over the middle section and wedged in against the same substantially in the same manner as the bottom section.

It will be seen that when the box is set up, it presents a firm and rigid construction 15 which is not easily deranged and which is as perfectly suitable for its purpose as a non-collapsible box of this type. Moreover, when the box is to be shipped or stored, the portions thereof may be collapsed so as to 20 occupy the minimum possible space required by the amount of material actually used in its construction.

Having thus described my invention, I claim as new—

- 25 1. A three part collapsible carton comprising separate collapsible top and bottom sections, and a separate collapsible middle section, said top and bottom sections being of exactly the same internal perimeter and 30 having means wherewith the middle section is wedged and held tightly in engagement.
2. A three part collapsible carton of corrugated material comprising separate collapsible top and bottom sections of the same 35 internal perimeter and having sides and end

portions, inwardly inclined resilient flaps extending from the end portions, and a separate collapsible middle section adapted to be forced in the top and bottom sections and wedged between said resilient flaps. 40

3. A three part collapsible carton of corrugated material comprising separate collapsible top and bottom sections of the same internal perimeter having sides and end portions, inturned resilient flaps extending 45 from the end portions, and a separate collapsible middle section adapted to be forced in the top and bottom sections and wedged between said resilient flaps.

4. A three part collapsible carton of corrugated material comprising top and bottom sections of exactly the same internal perimeter adapted to be collapsed to occupy the space of one thickness of the material, the end portions of said sections having resilient inturned flaps, and a separate collapsible middle section adapted to be forced in said top and bottom sections and wedged tightly between the resilient flaps, the entire box when collapsed and the sections thereof 55 placed one over the other occupying a space corresponding to the thickness of their material.

Signed at Baltimore, in the State of Maryland this 7th day of November A. D. 60 1912.

JOSEPH W. WEISS.
